UNITED STATES PATENT OFFICE.

SPENCER M. DUTY, OF CLEVELAND, OHIO, ASSIGNOR TO THE MEDAL BRICK AND TILE COMPANY, OF CLEVELAND, OHIO, A CORPORATION OF OHIO.

PROCESS OF FORMING FACE BRICK.

Application filed December 29, 1924. Serial No. 758,623.

To all whom it may concern:

Be it known that I, SPENCER M. DUTY, a citizen of the United States, residing at Cleveland, in the county of Cuyahoga and State of Ohio, have invented a certain new and useful Improvement in Processes of Forming Face Brick, of which the following is a full, clear, and exact description.

This invention relates to an improved process of forming face brick, such as enter into the construction of dwellings and other buildings.

The principal object of the invention is to provide a new process of making face brick, and in its more specific aspect, to provide certain improvements in the production of brick by the stiff mud process, by which process or improvements the appearance of the brick, both in texture and range of colors is greatly improved without, however, affecting the durability of the brick. More particularly, it is the aim of the invention to produce brick, the texture and color effects of which are such as to give a very pleasing appearance to the wall or building, and to overcome the objections to the brick which are used to a large extent at the present time, to-wit, the objectionable and monotonous shiny appearance of the die-surfaced brick and the mechanical roughness produced by scratching or wire-cutting the surface of brick, such as is done at the present time in the production of brick by the stiff mud process. The so-called dry press process and soft mud process are used less extensively than the stiff mud process, particularly as the shiny surface appearance of the brick formed by the first-named does not find as much favor with builders and architects.

As is well known, the brick produced by the stiff mud process are made by forcing clay or ground shale through a die by means of an auger, the clay being extruded from the die in the form of a continuous column which is cut into brick by means of wires.

As the brick produced by this method would, unless given a surface treatment either as the column is extruded or after cut into sections, have an objectionable shine and glisten, and would be so regular and smooth as to produce a monotonous, harsh wall, certain surface treatments have been resorted to. In some instances the surface of the column while being extruded is scratched by means of wires or nails, and in some in-

stances the surface of the column is removed or cut off by means of wires stretched across the mouth of the die, the former procedure producing what is known as "vertical texture" brick and the latter "mat texture" 60 brick. Though these brick are used very extensively, the roughness thus produced is considered mechanical.

In an attempt to overcome the mechanically roughened surface appearance of the 65 vertical texture and mat texture brick, sand has been used to break up the smooth die surface. Though by this process the shine is removed to some extent, nevertheless the brick thus produced are given only a thin 70 surface treatment, and after the brick are burned, the sand, or the major portion of it is readily rubbed off.

In accordance with my invention I depart 75 from the present practice of giving the brick simply a surface treatment in the ways mentioned above, by building up a new surface on the wet brick body, the surfacing material becoming an integral part of the brick. This is done by applying to the wet brick 80 body, and preferably on all surfaces thereof which are likely to be exposed in the wall, i. e. one side and the ends of the brick, a relatively dry, finely divided material having plastic qualities, or which when wet becomes 85 plastic. This is applied in appreciable thickness, preferably from one-sixteenth to one-eighth of an inch, so as to completely cover the original wet brick surface, which for reasons hereinafter explained, is prefer- 90 ably a mechanically roughened surface.

The material which is thus applied to the wet brick body is preferably the same material which forms the body, except that it is in a dry or relatively dry state and is more 95 finely screened than the ground shale or clay forming the body of the brick. That is to say, assuming that the brick is formed of ground up shale, (as the process is preferably carried out) ground shale screened to a 100 fineness such that it is substantially in the form of powder forms or constitutes the surfacing material, but no water is applied to it, as is done with the ground shale used in forming the body. I wish it to be understood, however, that although in the process as now carried out by me, the surfacing material is the same as is used in forming the body of the brick, except that it is in a 105 relatively dry and more finely divided state, 110

the essential characteristic is that the material be of a plastic nature, or that it has plastic qualities so that when it absorbs moisture from the body of the brick, it will adhere to it and become an integral part of it during the vitrifying process, which takes place in burning. In other words, it may be desirable to add one or more ingredients to the surfacing material which I preferably 5 employ, and the addition of any such ingredient I would regard as coming within the scope of my invention.

The stiff mud method by which vertical texture or mat texture brick are produced 10 is admirably adapted, with the addition of my present improvements, to my process, though the mechanical roughening is employed or utilized by me when the relatively dry surface material is applied for an entirely new purpose, i. e. to increase the bond 15 between the wet body and dry surfacing material.

The surfacing material is applied to the top and sides of the column, preferably after 20 the latter has been cut into brick sections, so that the dry material will not interfere with the cutting operation, or clog or break the wires used in cutting, and after it is applied to these surfaces of the cut column it is preferably rolled against the surfaces so 25 as to cause it to better adhere thereto and to have a substantially uniform depth.

The apparatus used in carrying out my invention may, of course, be varied very 30 extensively. Particularly is this true in regard to the apparatus used in forming the wet brick body, or the column when my improvements are utilized in conjunction with or in addition to the stiff mud process, 35 as is preferred. In the accompanying sheets of drawings I have illustrated certain apparatus used in the stiff mud process, and those portions of the apparatus which are standard practice in carrying out the stiff mud 40 process are shown only conventionally.

In the accompanying drawings, Fig. 1 is a side elevation showing so much of the apparatus as is necessary to an understanding 45 of the invention; Fig. 2 is a sectional view substantially along the line 2—2 of Fig. 1; Fig. 3 is an enlarged top plan view of that portion of the same utilized in applying the relatively dry surfacing material to the cut 50 column or wet brick bodies; Fig. 4 is a perspective view of the apparatus shown in Fig. 1; and Fig. 5 is a cross-sectional view just beyond the plow which levels off the dry material and scrapes the excess from the wet sectional column.

55 Referring now to the drawings, the part 10 at the left hand side of Fig. 1 represents the die through which the column 11 of wet clay or shale is extruded, the column passing out in a horizontal direction and traveling over a conveyor indicated at 12. The

part of the apparatus which receives the wet clay or shale, and which finally extrudes it in column form may be that commonly employed, and it is believed no illustration of it is necessary, it being understood 70 that the shale or clay is ground up and screened before being applied to the column-forming part of the apparatus where it is mixed with water applied in the right proportions.

75 As previously stated, the surface of the column is preferably mechanically roughened, and I might here state that in this instance this is done to increase the bond between the wet clay body and the relatively dry surfacing material. By proceeding in this manner my improved process can be carried out more effectively than if the dry finely divided material is applied to smooth and comparatively hard die surfaces of the column, and additionally I find that the finished brick has a more desirable appearance 80 or texture if the surfaces of the column to which the dry material is applied are first roughened. As the process is carried out 85 by me, the mat texture is given to the column by cutting off the top and side surfaces thereof with wires commonly employed for this purpose, and at 13 I have shown a frame holding the wires 14 which slice off material 90 from the top and sides of the column to produce the mat texture.

95 The column then passes through the cutting machine, indicated conventionally at 15, this machine in practice including an oscillatory frame with a series of taut piano wires, this frame moving forwardly with the column while the actual cutting is taking place, and then moving back to normal position, it being understood that the wires 100 are spaced apart a distance equivalent to the width of the brick sections to be formed from the column. Cutting machines of this type are well-known, and a diagrammatic or conventional illustration of the same in 105 Fig. 1 is thought to be sufficient. By this machine the column 11 is cut transversely into brick sections 16, of uniform width, these brick sections forming the body portions of the brick which are surfaced on the 110 ends and on one side, as will next be explained.

115 I find, as already stated, that if the dry material is applied to the column before it is cut into sections, it is liable to clog and otherwise interfere with the proper operation of the cutting machine. For that reason it is desirable that the column be cut into sections before the dry material is applied 120 to it, and therefore that sequence of operations is carried out by me in practice though I do not regard it as essential that the column be cut into sections before receiving the dry material.

125 Referring again to the drawings, it will 130

be seen that as here shown, the cut column next receives the surfacing material by being passed through the apparatus best shown in Figs. 3 and 4. This includes a hopper 17, 5 into which the dry and powdered or finely screened shale or other material is placed, which material, as already stated, is preferably the same as that which is employed to form the body of the brick. The cut or sectional column passes under this hopper, 10 through the equivalent of an open-ended trough, composed of a bottom plate 18 and upstanding side plates 19, the forward portions indicated at 19^a being preferably somewhat closer together than the rear portions, as shown in the drawings. The bottom of the hopper has a discharge mouth or outlet, the width of which is substantially the width of the column, and as the column 15 moves slowly under the hopper and through the trough, the dry material is deposited on it, the rate of flow being determined by a vertically adjustable slide 20, which serves also as a scraper or leveler, scraping the excess material off the top of the column and causing it to fall down into and fill the space between the column and the side plates 19, so that the dry material may attach itself 20 not only to the top surface of the cut column, but also to the sides. In other words, as the cut column passes through the trough and under the hopper, the top and sides thereof virtually pass through a body of the surfacing material. By capillary 25 traction the moisture in the wet column penetrates the dry material, and a certain bond is formed at this point, causing the surfacing material to attach itself to the column.

40 Forwardly of the slide 20 there is a vertically adjustable wedge-shaped plow 21, which further levels off the top surface and determines the amount of material left thereon, the excess being scraped off and 45 falling between the column and the side plates 19.

Forwardly of the plow, the surfacing material not wet to a degree, is compacted by rollers, including two vertically disposed 50 rollers 22, which engage the sides of the now coated column, and a horizontal roller 23 which rolls down the surfacing material on the top of the column. Preferably the side rollers are pressed inwardly against the 55 sides of the column through the medium of springs, and preferably the roller 23 is pressed down by its own weight, or by gravity, the side rollers being in this instance supported in pivoted brackets 24, and the 60 top or horizontal roller 23 in slots of standards 25. By the action of these rollers the bond is increased between the surfacing material and the column.

When the sectional column passes these 65 rollers, the top and sides thereof are covered to a practically uniform depth, which may be varied from approximately one-sixteenth of an inch or less to some predetermined greater thickness, such as one-eighth of an inch. In any event, the previously roughened top and side surfaces are completely covered by a coating of the surfacing material, of an appreciable thickness such as that 70 stated above.

A short distance forwardly of the roller 75 23, the column rides off the bottom plate 18 onto a traveling belt 26, which moves somewhat faster than the column moves when sliding over the bottom plate 18, so that as the brick engage this belt they are separated, 80 as indicated in Fig. 3, and can be removed from the belt and placed on a car for further treatment.

The coated or surfaced brick are next 85 placed in a drier, where the so-called mechanical water is removed. In the drying process, as the excess moisture or mechanical water in the wet brick passes therefrom, it more thoroughly moistens the surface material and still further increases 90 the bond between it and the brick body beneath.

After being dried, the brick are burned, 95 and by the vitrifying process in the burning, practically a uniform or homogeneous fusion is obtained between the brick body and the surfacing material, the latter becoming an integral part of the brick, but there is, nevertheless, produced a texture and a range 100 of colors at the surface which are peculiar to brick formed in this manner and more pleasing and satisfactory than in the brick formed by the prior known processes.

Having described my invention, I claim:

1. The process of producing face brick, 105 which comprises forming a brick body of wet plastic material, applying to the surface thereof relatively dry and finely divided material having plastic qualities, and burning the bricks so as to cause a uniform and substantially homogeneous structure between the body and surfacing material.
2. The process of producing face brick, 110 which comprises forming a brick body of wet stiff plastic material, applying to the wet surface of the brick a relatively dry finely divided material having plastic properties so as to form a surface covering of appreciable thickness, compacting the material thus applied to increase the bond between the said material and brick body, and burning the brick so as to form a permanent union and substantially uniform brick structure from the material forming the brick body and that added to it.
3. The method of producing face brick, 115 which comprises forming a brick body of wet stiff plastic material, covering portions of the surface thereof with the same or substantially the same material in a relatively 120

dry and finely divided state so as to completely cover such portions of the surface, and then treating the brick so as to vitrify the material and cause the surfacing material to become an integral part of the brick body.

4. The method of producing face brick, which comprises forming a brick body of stiff wet plastic brick-forming material, applying to portions of the surface thereof in appreciable thickness a relatively dry finely divided material having plastic qualities, rolling the material in contact with the brick body, and then treating the composite

10 brick thus formed so as to vitrify the materials and cause a substantially homogeneous structure.

5. The process of producing face brick, which comprises extruding a column of wet stiff brick-forming material adapted to be cut into sections, applying to portions of the surface thereof in appreciable thickness a relatively dry finely dividing brick-forming material having plastic qualities so that it

20 25 will adhere to the wet surface, compacting it onto the wet surface, and then vitrifying the materials and thereby causing the surfacing material to become an integral part of the brick structure.

30 6. The process of producing face brick, which comprises extruding a column of wet stiff brick-forming material adapted to be cut into sections, applying to portions of the wet surfaces thereof a relatively dry finely

35 divided material having plastic qualities of the same or substantially the same composition which entered into the formation of the column, compacting the material thereon, and burning the brick thus formed so as to

40 cause the surfacing material to become an integral part of the brick and a substantially uniform or homogeneous structure with the original brick body.

7. The process of producing face brick, 45 which comprises forming a column of stiff wet plastic brick-forming material, cutting the column into sections, applying to portions of the surfaces thereof in appreciable thickness so as to cover said portions, a relatively dry finely divided material of the same or substantially the same composition as that of which the column is formed, and burning the brick so as to cause the surfacing material to become an integral part of it

55 and a uniform or substantially homogeneous structure with the brick body.

8. The process of producing face brick,

which comprises extruding a column of stiff wet plastic brick-forming material, cutting the same into sections as it is extruded, applying to the top and sides of the section or column after being cut into sections, relatively dry finely divided brick-forming material of the same or substantially the same composition as that which entered into the formation of the column, compacting the material on said surfaces, and then burning the composite bricks thus formed so as to cause the surfacing material to become an integral part thereof and to form a substantially uniform structure with the original wet brick body.

9. The process of producing face brick, which comprises forming a brick body of wet plastic material and with a roughened surface, applying to the surface thereof relatively dry and finely divided material having plastic qualities, and burning the bricks so as to cause a uniform and substantially homogeneous structure between the body and surfacing material.

10. The process of producing face brick, which comprises extruding a column of wet stiff brick-forming material adapted to be cut into sections, roughening the surface of the column while being extruded, applying to portions of the surface thereof in appreciable thickness a relatively dry finely divided brick-forming material having plastic qualities, so that it will adhere to the wet surface, compacting it onto the wet surface, and then vitrifying the materials and thereby causing the surfacing material to become an integral part of the brick structure.

11. The process of producing face brick, which comprises extruding a column of stiff wet plastic brick-forming material, roughening the surface of the column while being extruded, cutting the same into sections as it is extruded, applying to the top and sides of the section or column after being cut into sections relatively dry finely divided brick-forming material of the same or substantially the same composition as that which entered into the formation of the column, compacting the material on said surfaces, and then burning the composite bricks thus formed so as to cause the surfacing material to become an integral part thereof and to form a substantially uniform structure with the original wet brick body.

In testimony whereof, I hereunto affix my signature.

SPENCER M. DUTY.
